(57) **CLAIM**

The ornamental design for a bottle, as shown and described.

DESCRIPTION

FIG. 1 is a top front perspective view of a bottle showing our new design;

FIG. 2 is a bottom rear perspective view thereof;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a top plan view thereof;

FIG. 8 is a bottom plan view thereof;

FIG. 9 is a top front perspective view of the bottle in a second position;

FIG. 10 is a front elevational view of the bottle in the second position;

FIG. 11 is a left side elevational view of the bottle in the second position;

FIG. 12 is a right side elevational view of the bottle in the second position; and,

FIG. 13 is a top plan view of the bottle in the second position.
